DESIGN FOR A TOY HELICOPTER

Frank Mitschang, Buffalo, N. Y.

Application January 9, 1946, Serial No. 125,380

Term of patent 3½ years

(Cl. D34—15)

To all whom it may concern:

Be it known that I, Frank Mitschang, a citizen of the United States, residing at Buffalo, in the county of Erie and State of New York, have invented a new, original, and ornamental Design for Toy Helicopters, of which the following is a specification, reference being had to the accompanying drawing, forming part thereof.

In the accompanying drawing:

Fig. 1 is a side elevation of a toy helicopter, showing my new design.

Fig. 2 is a top plan view thereof.

Fig. 3 is a front elevation thereof.

I claim:

The ornamental design for a toy helicopter, as shown.

FRANK MITSCHANG.
